BOBBIN TRANSFER FEELER

Application filed August 29, 1927. Serial No. 216,201.

This invention relates to transfer mechanism for automatic looms of the type wherein when the thread on the bobbin is almost exhausted, the empty or nearly empty bobbin 5 is forced out of the shuttle by the full bobbin which is forced into its place in the jaws of the shuttle by suitable mechanism.

There are several types of looms and there are several types of feeler mechanism both 10 well known. The purpose of the feeler is to come in contact with the thread on the bobbin every time the lay beats up or every other time, and when the thread has run off to a 15 pre-determined amount this feeler acts in a somewhat different manner and indicates transfer which means setting in operation a train of mechanism to make the transfer of bobbins usually at the next beat up.

This invention relates to the feeler finger 20 and the slide which carries it.

I provide a feeler slide slidable on the breast beam in a direction corresponding with the movement of the lay beam and having a slide spring adapted to normally keep the 25 slide towards the lay beam and a feeler finger preferably made of fiber, pivoted at one end to the slide and having on its free end at one side a smooth rounded heel, and on the other side one or more teeth which, while there is 30 a certain amount of thread on the bobbin, keep it from slipping or pivoting sideways, but when the thread has been exhausted to a pre-determined amount will slip sideways on the bare barrel of the bobbin.

The finger is so pivoted that a line which 35 passes through its pivot in the same direction as the movement of the lay beam will pass back of the front tooth. With this arrangement, when there is enough thread on the 40 bobbin to prevent the finger from moving sideways, it will force back the slide with the lay beam but when the amount is sufficiently reduced, it will slip sideways.

There are certain types of feelers known as the "side-swipe" type but my device has certain advantages.

The slide and its accompanying parts are 45 very much simplified and can be coupled up to the other parts of looms of various types

in such a way as to reduce the amount of mechanism.

Where sharp metal teeth are used on a 55 feeler finger, they have a tendency to scratch and injure the bobbin, which is highly objectionable especially with fine silk or rayon.

I so form the tip of my feeler finger that the teeth cannot scratch the bobbin even when in contact therewith as they either move directly back with it or when the finger pivots, the teeth as they swing, recede from the lay beam bringing the smooth heel alone in contact therewith.

To still further improve the device I prefer 60 to make it of hard fiber.

Silk and rayon are of such character that 65 they must be wound very hard and close on the bobbin and I have found that any feeler device which to operate must penetrate the yarn package will quickly cut the threads and 70 operate improperly.

On the other hand on such yarn packages unless the feeler tip is so made that it will 75 not slip, it will pivot too soon and cause a full bobbin to be ejected.

By making the tip or contacting end of 80 my feeler in a peculiar form, I avoid both of the above objections.

In the drawings, Fig. 1 is a side elevation 85 showing part of a lay beam in section and my device applied to a well known type of automatic loom known in the trade as a Draper loom.

Fig. 2 is a fragmentary perspective view 90 of parts of the same type of loom with my device attached.

Fig. 3 is a plan view showing some of the parts such as are shown in Fig. 1.

Fig. 4 is an enlarged plan detail view 95 showing part of the slide and my feeler finger in contact with a bobbin. The full lines show the position of the feeler and slide when pushed back by the advancing lay while there is yarn on the bobbin, and the dotted lines show the position assumed by the feeler when it swings or slips over when there is little if any yarn on that part of the bobbin with which it comes in contact.

Fig. 5 is an enlarged plan view showing 100 the feeler finger tip with teeth.

Fig. 6 shows my device applied to the opposite side of a loom, of the type shown in Figs. 1, 2 and 3.

Fig. 7 is a view similar to Fig. 1 showing my device applied to another type of automatic loom.

Fig. 8 is an enlarged elevation partly in section, showing the pivot end of my feeler.

In the drawings, I show only such parts of automatic or bobbin changing looms as seem necessary to understand the device.

In Fig. 2, 40 represents the breast beam forming part of the frame of what is known as a Draper loom which carries a battery, not shown, filled with full bobbins 18 in the usual manner.

To it is pivoted at 120 the transfer hammer 20 which has the usual heads or other suitable devices 220 for forcing a full bobbin such as 18 out of the battery and pushing down through the shuttle 22 an empty bobbin or almost empty bobbin 17. This transfer hammer also has an operating arm 320 which extends downward as shown, and to this is pivoted at 420 a transfer dog 6 which automatically is held up by a tension spring 12 so that its nose 6A will normally be in position so that the dagger 8 carried by the lay beam 21 would normally engage it and as its upward pivotal movement is limited by stop 112, the forward motion of the lay beam will force back arm 320 and therefore downward the head 220 if the dog 6 or its nose 6A is not moved out of the way of dagger 8.

A represents a detector bed which is usually pivoted to the breast beam at 1 and either held rigidly as by a set screw 24 or normally held down by a tension spring 19. The above parts are all substantially old.

B is a detector slide slidable in or on detector bed A in suitable ways in a direction substantially perpendicular to the lay beam 21 but preferably directed in line with its forward and back movement. This slide when moved back projects and will move back or forward toward the front of the loom, and is shown as extending beyond detector bed A and as being provided with a returning spring 5 which normally pushes it towards the lay beam. It also has a downwardly projecting arm 100 from which horizontally projects a slide stud 14 which passes through a loop 13 in connecting rod F to be described. There is also an adjusting screw 10 by which the position of slide B can be more or less regulated.

The other end 113 of connecting rod F is pivoted at 16 to a stud on one side of dog 6 which is preferably a greater distance from the center of the hammer pivot 120 than is the center of the pivot 420 for the dog itself so that as the dog and arm 320 move back this connecting rod will move over a greater arc than the nose 6A as indicated by the arcs shown in Fig. 1.

At the side of the loom opposite battery 41 is a shuttle binder 26 of any usual form adapted to be pushed somewhat out when the shuttle enters the box on that side, and G represents broadly the connection between this side of the loom and dog 6. As shown, shuttle binder 26 is pivoted at 126 to lay beam 21 and against this bears an arm 25 adjustably fixed to a rod 124 which extends across the loom, being carried in suitable hangers 224 on breast beam 40 and having at its battery end an arm 11 of bifurcated form having a slot 111 into which passes a stud or roller 15 which projects from dog 6 on the opposite side from stud 16.

It will be seen that when connecting rod F is pushed toward the front of the loom, or when shuttle binder 26 is pushed in that direction by the entry of a shuttle, in either case dog 6 will be pulled down on its pivot 420 so that its nose 6A will be out of the way of dagger 8. Shuttle binder 26 will act on each alternate pick and I will now describe my detector device on the side of the battery.

C represents a detector finger pivoted at one end on pivot 101 to the end of slide B which is next to the lay beam, and this has a shoulder 102 on what I will call the inside of the loom which is the side where the heads such as 118 of the bobbins are positioned in the magazine or battery. Its free end 107 curves away from the inside or from the head of the bobbin when in position away from the center of the loom, and this end is provided on the side next such heads with a smooth, rounded heel 104, and outside of such heel, that is away from the center of the loom, there are one or more teeth 103, 203, 303.

This end of the feeler or detector finger C should be carefully made so that one of these teeth 103 will engage the thread such as K if there is any on the bobbin but when they come in contact with a place where there is no thread K or where it is very thin, as at 170, the tooth 103 will slip away from the head of the bobbin with a result to be described.

Each finger C has on the outside a shoulder 102 which by means of a coiled spring 4 is kept in adjusted contact with a stop 9 on slide B. The position of stop 9 can be regulated by a screw 109 so that as shown in Fig. 4, the contact point of finger C which is ordinarily the front and longest of the teeth 103 will engage the thread K on the bobbin and so that as the lay beam advances, this thread will prevent the finger C from doubling up or bending toward the outside of the loom and away from the bobbin head 118 but will force before it, finger C and slide B carrying with them the connecting rod F and depressing dog 6.

This occurs at every alternate pick until the amount of thread K is reduced to such a point, as indicated at 170, on the bobbin that, as teeth 103, 203, 303, find nothing to stop

them, heel 104 slides over with the result that slide B is not moved and dog 6 is not moved whereupon dagger 8 acts upon the nose 6A of the dog and causes a full bobbin to replace an empty bobbin in a well known manner.

5 The provision of slot 13 allows slide B to move quite a distance before dagger 8 engages the dog 6, and also allows of the operation of means G at the other side of the loom to pull the dog out of position on the alternate picks.

10 On looms where the detector mechanism is on the side opposite the battery, it is not necessary to remove the feeler tip or feeler finger from contact with the nearly empty bobbin because the transfer is not made until the shuttle returns to the battery side of the loom.

15 With this device however it is necessary to move the detector finger out of the way of the entering full bobbin or it would be in danger of breakage. I accomplish this by positioning the pivot point 16 of connecting rod F and slide stud 14 farther from pivot 120 of the transfer hammer than pivot point 420 of the dog and farther than the dog nose 6A from 20 120 so that when the dagger 8 begins to force back the dog 6, on account of the greater radius, the slide B and finger C move a greater distance than the dagger 8 moves and the free end or tip 107 is therefore pulled out of the way of the incoming full bobbin. This relation is shown by the arcs X and Y in Fig. 1.

25 The parts shown and described particularly in Figs. 1, 2 and 3 are shown and claimed in my copending application on transfer mechanism for looms filed Sept. 17, 1927, Ser. No. 220,143, Patent No. 1,781,514. The feeler finger which is also shown and which I will now describe more particularly can also be 30 used however in other places and with other types of looms.

35 Preferably the feeler finger C is very carefully made of hard fiber and carefully adjusted so that a line such as shown in the long dashes O of Fig. 4 passing through pivot 101 in the same direction as the movement of the lay beam will pass back of the front which should be the longest of the teeth between it and heel 104.

40 This front tooth 103 preferably has a flat face at substantially right angles with the line of movement of the lay beam indicated by O and substantially parallel with the barrel of a bobbin as shown in Fig. 4 or is curved and blunt as shown in Fig. 5. It is so made in order that it will not cut the finest yarn even when it strikes in the same place on the yarn mass at every pick. By so making this contact tooth, it is unnecessary to use the intermittent action used with some feelers as for instance that shown in patent to Landry No. 1,420,560, June 20, 1922.

45 These parts should be so adjusted that the front end of each tooth 103, 203, 303, will engage some of the fine threads 180 but will not

dig into the wood of the bobbin, while the following teeth are positioned slightly further away from the bobbin so that when feeler finger C does pivot at 101 the teeth will swing away from the bobbin 17 as shown 70 by the arcs T, S and R.

75 By making the front or longest tooth 103 flat faced or blunt and by adjusting the angle between it and line O with reference to pivot 101 to be very acute, or to put it in another way, to make the line from 103 to 101 a very little off center and by making the feeler return spring 4 very weak as by adjustment through set screw 100 shown in Fig. 8, the feeler finger C does not slip sideways until it strikes the bare wood and as the other teeth 203 and 303 are set well back therefrom, when the finger C pivots, these other teeth scarcely touch the wood or if they do touch it at all, it is at the left of 80 where 103 struck.

85 On the other hand however, if there is any irregularity in the yarn mass in front of tooth 103 or if the yarn is wound in a series of cones such as is known as the "universal wind" or if the end of the barrel near the head is conical, these other teeth overcome the tendency which there might be for this angular contact with the front tooth to move it sideways before it should move.

90 These factors of the flat or blunt face of the long tooth and the other teeth being relatively sharper but set well back therefrom, the adjustment slightly off center and especially making the finger of the fiber all contribute to prevent scratching of the bobbin and accurate functioning with a minimum of waste.

100 In Fig. 6, I show my feeler mechanism applied to the side of a Draper loom which is opposite from the magazine in place of any of the various feeler devices now used on that type of loom.

105 21 is the lay beam and 18 represents a full bobbin in a shuttle which is held in position by the usual shuttle binder such as 50 while 51 is a bracket which is bolted to the breast beam indicated by 40, which bracket carries the detector bed 52 which is substantially similar to A and carries slidably the detector slide B, which in turn carries the feeler finger C.

110 Detector bed 52 also has an ear 53 with a bearing through which is slidably a rod 54 which extends across the loom and connects with the regular transfer mechanism on the battery side in a well known manner. This ear 53 is in position a little closer to the lay beam, than pivot 101 so that when finger C bends over or pivots away from the head of the bobbin 18 it pushes rod 54, and as it is expressed "indicates transfer".

115 In Fig. 7, I show part of what is known as a Crompton and Knowles loom or loom of the type in which the transfer hammer such 120

as 60 is operated by other means connected with the magazine, generally known as a lifting rod or actuator.

In this case, 61 is the breast beam and 62 5 the lay beam while the full bobbin is indicated by 18 as before.

The detector bed A is the same as in the first described construction as is also the slide B and finger C.

10 The back end of the slide when it is moved back is in position to engage a lever arm 63 which is moved backward at every alternate pick until transfer is to be indicated, at which time finger C doubles up, and as 63 is 15 not moved, the train of mechanism which is well known as see patent to Ryon on weft replenishing loom, No. 972,722, of Oct. 11, 1910, and which it is not necessary to show, is started in operation to actuate hammer 20 60 and transfer the bobbins.

When this starts to occur, as the feeler is in the shuttle slot, it is necessary to move the finger out of the slot in the shuttle 64 before the hammer descends upon the bobbin, as 25 otherwise there would be a smash up.

I accomplish this by using the pin 65 on the arm 66 of the transfer hammer and by placing in position on slide B a stud 67 which pin 65 engages as the transfer hammer is 30 coming down at the time of transfer, thus moving back slide B and finger C, and avoiding any smash up.

Preferably I cut the contact end or tip 107 as shown in Figs. 4 and 5 from 104 to 204 35 on a parabolic or elliptical curve or on an arc the focus or centre of which is at a point such as generally indicated at V which is in front of a straight line through pivot 101 in the direction of the movement of the lay beam and is located in the direction in which 40 the feeler pivots. By "focus" I include the centre of a circle.

This curve normally rises back away from the bobbin and the teeth 103, 203 and 303 45 are cut so that their front faces are at right angles to the bobbin or rake or hook slightly forward and their points successively recede from the forward tooth.

Thereby, whatever wear there is will not 50 dull the teeth. Moreover when tooth 103 touches a bare spot on the bobbin, and the feeler starts to turn on a bobbin having a universal cone wind, teeth 203 engages the 55 yarn and then tooth 303 or on a smooth, hard silk or rayon yarn package, as the feeler starts to turn, all three teeth will engage and stop it until they all engage a bare spot on the bobbin.

My slide return spring 5 should be a little 60 stronger than feeler return spring 4 but both can be very weak as it is not necessary to force the feeler teeth between nor into the yarn package and this reduces any tendency to cut the yarn even if a steel feeler is used.

65 My whole feeler can be adjusted laterally

or cross-wise and also circumferentially on the breast beam at 1 by means of the set screw 24 and the longitudinal or forward and back position of slide B can be regulated by adjusting screw 10 whereby the position of contact of the feeler finger tip with the yarn on the bobbin and the extent of movement of slide B can be regulated.

The angular relation between the front tooth, the pivot 101 and the line of movement O can be adjusted by means of the stop 9 and stop screw 109 while the strength of the feeler return spring 4 can be regulated by head 200 which holds the end 207 of spring 4, the other end 208 engaging feeler finger C as shown in Fig. 8, together with the set screw 100 which passes through this head and engages the pivot post 101.

I claim:

1. In a filling changing device for automatic looms having a lay beam and a battery on the breast beam, the combination with a slide movable on the breast beam towards and from the lay beam in the same direction as the movement of the lay beam, and having an 90 adjustable detector finger stop, and a spring adapted to move the slide towards the lay beam; of a fiber feeler finger having a shoulder on the side away from the battery in engagement with said stop and having its free 95 end formed with a smooth rounded heel on the side of the shoulder and teeth on the other side thereof the front tooth being the longest, said finger being so pivoted to the slide that a straight line through the pivot in the direction of the movement of the lay beam passes back of the front tooth so that when the finger moves on its pivot away from the stop, the teeth, will recede from the lay beam; and a 100 feeler return spring.

2. In a filling changing device for automatic looms, the combination with a slide movable on the breast beam towards and from the lay beam in the same direction as the movement of the lay beam, and having a detector finger stop, and a spring adapted to move the slide towards the lay beam; of a fiber feeler finger having a shoulder in engagement with said stop and having its free 110 end formed with a smooth rounded heel on the side of the shoulder and teeth on the other side thereof the front tooth being the longest, said finger being so pivoted to the slide that a straight line through its pivot in the direction of the movement of the lay beam passes back of the front tooth so that when the finger moves on its pivot away from the stop, the teeth will recede from the lay beam 120 and a feeler return spring.

3. In a filling changing device for automatic looms, the combination with a slide movable on the breast beam towards and from the lay beam in the same direction as the movement of the lay beam, and a spring adapted to move the slide towards the lay 130

beam; of a fiber feeler finger having its free end formed with a smooth rounded heel and teeth on the other side thereof the front tooth being the longest, said finger being so pivoted to the slide that a straight line through its pivot in the direction of the movement of the lay beam passes back of the front tooth so that when the finger moves on its pivot away from the stop, the teeth will recede from the lay beam; and a feeler return spring.

4. In a filling changing device for automatic looms, the combination with a slide movable on the breast beam towards and from the lay beam in the same direction as the movement of the lay beam, and a spring adapted to move the slide towards the lay beam; of a fiber feeler finger having its free end adapted to engage a bobbin carried in a shuttle on the lay beam having a smooth rounded heel on the side towards the bobbin head and teeth on the other side thereof the front tooth being the longest, said finger being so pivoted to and held on the slide that a straight line through its pivot in the direction of the movement of the lay beam passes back of the front tooth so that when the finger moves on its pivot away from the stop, the teeth will recede from the lay beam; and a feeler return spring.

5. In a filling changing device for automatic looms, the combination with a slide movable on the breast beam towards and from the lay beam in the same direction as the movement of the lay beam; of a feeler finger having its free end adapted to engage a bobbin carried in a shuttle on the lay beam and being movable on a pivot near its other end fixed on said slide, and cut at said free end on a curve the focus of which is in front of a straight line drawn through said pivot in the direction of the movement of the lay beam, such curve extending in front of said line and having teeth cut out of the curved part which rake away from said line and which have their points successively receding from the forward tooth.

6. In a filling changing device for automatic looms, the combination with a slide movable on the breast beam towards and from the lay beam in the same direction as the movement of the lay beam; of a feeler finger having its free end adapted to engage a bobbin carried in a shuttle on the lay beam and being movable on a pivot near its other end fixed on said slide, and cut at said free end on a curve the focus of which is in front of a straight line drawn through said pivot in the direction of the movement of the lay beam, such curve extending in front of said line and having teeth cut out of the curved part.

7. A feeler finger having near one end a pivot and having its other end cut on a curve the focus of which is at a point different from said pivot and having teeth cut out of the

curved part and successively receding from the end, the tooth nearest the end being blunt.

8. A feeler finger having at one end a pivot and having its other end cut on a curve the focus of which is at a point different from said pivot and having teeth cut out of the curved part, the tooth nearest the tip being blunt and the others relatively sharp.

9. A fiber feeler finger having near one end a pivot and proximate said pivot an adjusting shoulder and having its other end cut on a curve the focus of which is at a point different from said pivot and having teeth cut out of the curved part, the tooth nearest the tip being blunt.

10. In a filling changing device for automatic looms, the combination with a slide movable on the breast beam towards and from the lay beam in the same direction as the movement of the lay beam, and a spring adapted to move the slide toward the lay beam; of a fiber feeler finger having its free end adapted to engage a bobbin carried in the shuttle on the lay beam and having a smooth rounded heel on the side towards the bobbin head and teeth on the other side thereof the end tooth being the longest and being blunt, said finger being so pivoted to and held on the slide that a straight line through its pivot in the direction of the movement of the lay beam passes back of the end tooth so that when the finger moves on its pivot away from the bobbin head the other teeth will recede from the lay beam; means carried by the slide to adjust the angle between the feeler finger and the slide; and a feeler return spring.

11. In a filling changing device for automatic looms, the combination with a slide movable on the breast beam towards and from the lay beam in the same direction as the movement of the lay beam, and a spring adapted to move the slide towards the lay beam; of a fiber feeler finger having a free end which terminates in a blunt tooth adapted to engage a bobbin carried in a shuttle on the lay beam and having a smooth rounded heel proximate said tooth on the side towards the bobbin head, said finger being so pivoted to and held on the slide that a straight line through its pivot in the direction of the movement of the lay beam passes back of the end tooth; means carried by the slide to adjust the angle between the finger and the slide; a feeler return spring; and means to adjust the strength of the feeler return spring.

12. In a filling changing device for automatic looms, the combination with a slide movable on the breast beam towards and from the lay beam in the same direction as the movement of the lay beam, and a spring adapted to move the slide towards the lay beam; of a fiber feeler finger having a free end which terminates in a blunt tooth adapt-

ed to engage a bobbin carried in a shuttle on the lay beam and having a smooth rounded heel proximate said tooth on the side towards the bobbin head, said finger being so pivoted to and held on the slide that a straight line through its pivot in the direction of the movement of the lay beam passes back of the end tooth; means carried at its top by the slide to adjust the angle between the finger and the slide; a feeler return spring; and means carried at its top by the slide to adjust the strength of the feeler return spring.
